UNITED STATES PATENT OFFICE

121,411

DESIGN FOR A COMBINED SEAT, SCORE
TABLE, AND BOWLING ALLEY SERVICE
UNIT OR SIMILAR ARTICLE

Andrew L. Henkel and Burke M. Ewing, Chicago, Ill., assignors to The Brunswick-Balke-Col-lender Company, Chicago, Ill., a corporation of Delaware

Application April 10, 1940, Serial No. 91,573

Term of patent 14 years

To all whom it may concern:

Be it known that we, Andrew L. Henkel and Burke M. Ewing, both citizens of the United States and both residing in the city of Chicago, in the county of Cook, State of Illinois, have jointly invented a new, original, and ornamental Design for a Combined Seat, Score Table, and Bowling Alley Service Unit or Similar Article, of which the following is a specification, reference being had to the accompanying drawing forming a part thereof.

seat, score table, and bowling alley service unit or similar article, showing our new design;

The opposite side of the device is substantially the same as that shown.

We claim—

The ornamental design for a combined seat, score table and bowling alley service unit or similar article, as shown and described.
